UNITED STATES PATENT OFFICE

107,582

DESIGN FOR A JAR OR SIMILAR CONTAINER

Walter F. Straub, Chicago, Ill., assignor to W. F. Straub & Company, Chicago, Ill., a corporation of Illinois

Application April 26, 1937, Serial No. 68,971

Term of patent 14 years

To all whom it may concern:

Be it known that I, Walter F. Straub, a citizen of the United States, residing at Chicago, in the county of Cook and State of Illinois, have invented a new, original, and ornamental Design for a Jar or Similar Container, of which the following is a specification, reference being had to the accompanying drawing, forming a part thereof.

Fig. 2 is a side elevational view of the container shown in Fig. 1.

Fig. 3 is a top plan view of the container.

The design is characterized by the provision of a rectilinear body portion and a relatively short round neck portion closely set upon the body portion and of such size as to extend outwardly beyond the planes of two opposite faces of the body portion.

I claim:

The ornamental design for a jar or similar container substantially as shown and described.

WALTER F. STRAUB.
